(57) **CLAIM**

We claim, the ornamental design for a luminaire, as shown and described.

DESCRIPTION

FIG. 1 is a perspective view of a luminaire, showing our new design;

FIG. 2 is an enlarged top plan view thereof, shown broken away for convenience of illustration;

FIG. 3 is an enlarged side elevation view thereof shown broken away for convenience of illustration;

FIG. 4 is a perspective view of a luminaire, showing our new design in another embodiment;

FIG. 5 is an enlarged top plan view thereof, shown broken away for convenience of illustration; and,

FIG. 6 is an enlarged side elevation view thereof shown broken away for convenience of illustration.

The broken lines shown in the drawings illustrate portions of the luminaire that form no part of the claimed design.
